GRAVITY GRAIN GRADER COMPANY, OF STOCKTON, CALIFORNIA, A CORPO-
RATION OF CALIFORNIA.

ROTARY SCREEN.

1,373,841.

Specification of Letters Patent.

Patented Apr. 5, 1921.

Application filed April 17, 1919. Serial No. 290,655.

To all whom it may concern:

Be it known that we, JOHN M. STONE and AVON L. STONE, citizens of the United States, residing at Stockton, in the county of San Joaquin and State of California, have invented certain new and useful Improvements in Rotary Screens, of which the following is a specification.

The invention is primarily designed to provide a grain cleaning screen of the rotary type which embodies a substantial frame-work and a screening surface of wire, the frame-work being expandable to admit of subjecting the screening surface to proper tension, said screening surface preferably consisting of a wire which is wrapped about the frame-work and secured in any suitable way thereto at its ends, the screen comprising a plurality of sides.

The invention furthermore aims to provide a separating screen which may be constructed at a comparatively small cost and which provides for subjecting the screen surface to any degree of tension so as to obtain the best possible results in the operation and working of the screen.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the drawing hereto attached, Figure 1 is a side view of a rotary separating screen embodying the invention and having the major portion of the screen surface omitted to bring out more clearly the construction of the frame-work.

Fig. 2 is an end view and

Fig. 3 is a detail perspective view of a portion of one of the ribs.

Corresponding and like parts are referred to in the following description and indicated in the several views of the drawing by like reference characters.

The screen comprises a shaft 1 which in the preferable construction consists of a pipe or tube of suitable length and diameter. A plurality of collars 2 is secured on the shaft 1 by means of set screws 3 or other suitable fastening means. Arms 4 have their inner ends let into openings formed radially in the

collars 2 and their outer ends are forked, as indicated at 5 to receive ribs 6 which are of V or angle form and disposed with their hollow sides facing outwardly. The inner ends of the arms 4 are threaded for a short distance, as indicated at 7 and receive adjusting nuts 8 by means of which the arms 4 may be moved radially. The ribs 6 extend in parallel relation to one another and to the shaft 1 and are secured to the outer ends of the arms 4 in any way. By having the ribs 6 formed of V or angle iron, a light and durable structure results. The outer edges of the wings or flanges of each of the ribs 6 are formed with notches 9, as indicated most clearly in Fig. 3 to receive the wire 10 which constitutes the screen surface, thereby holding the windings of the wire in fixed relation.

The wire 10 may be of any gage or material and preferably consists of steel wire 19 gage which is secured at one end and after being wrapped around the ribs is made secure at the other end. The shaft 1, collars 2, arms 4 and ribs 6 constitute the frame-work of the screen and the wire 10 wrapped around the frame-work forms the screen surface, the spaces between the winds being determined by the distance between the notches 9 and forming the escape for cracked grain and other material to be separated from the selected grain which passes through the screen and is delivered from the discharge end thereof.

Strips 11 are interposed between adjacent ribs and are disposed diagonally or at an inclination, as indicated most clearly in Fig. 1. The strips 11 have their ends bent and secured to the sides of adjacent ribs by suitable fastening means. These strips 11 are provided for every alternate pair of ribs, as shown most clearly in Fig. 2, the intermediate pairs of ribs being free from such strips, whereby an unobstructed passage is provided for the delivery of the grain. The strips 11 are spaced from the screening surface 10 a distance to provide for a passage of a layer of grain, thereby insuring a thorough separation of broken grain, weeds and other small particles required to be separated from the selected grain.

After the wire 10 is wrapped around the ribs of the screening frame, the latter is expanded to tighten the screen surface by ap-

plying a wrench or other tool to the nuts 8 and turning the same to move the arms 4 and the ribs 6 outwardly. It will be understood that the screening surface may be subjected to any required tension. The space between adjacent ribs corresponds to a side, hence the screen may have any number of sides depending upon the number of arms associated with each of the collars. The screen indicated has six sides; hence is of hexagonal form, but it is to be understood that the polygonal form of the screen may vary as required.

In the operation of the screen the same is rotated about 14 revolutions per minute which allows grain sufficient time to slide down the wires comprising the screening surface without throwing the same. The grain to be cleaned and separated enters one end of the screen and as the screen rotates slowly one side after another rises, thereby causing the grain to slide downward. As the grain slides down the inclined side a certain amount passes beneath the strips 11, but the bulk of the grain passes along the side of the strips 11, and is driven by them in the direction of the discharge end of the screen. This skimming process allows a uniform stream of grain to slide from one side of the screen to the next and at the same time keeps a steady flow of grain moving toward the delivery end.

The foregoing description and the drawing have reference to what may be considered the preferred, or approved form of our invention. It is to be understood that we may make such changes in construction

and arrangement and combination of parts, materials, dimensions, et cetera, as may prove expedient and fall within the scope 40 of the appended claims.

Having thus fully described our invention, what we claim as new and desire to secure by Letters Patent is:—

1. A rotary screen comprising a plurality 45 of ribs disposed about an axial support, screen surfaces supported by the ribs, and diagonally disposed strips successively arranged between alternate pairs of ribs and spaced from the screening surfaces to provide means for advancing material from the receiving end of the screen to the discharge end.

2. A rotary screen, comprising a plurality of ribs disposed about an axial support, a 55 screen surface supported by the ribs and inclined strips between every alternate pair of ribs and spaced from the screen surface to successively advance the screen contents toward the discharge end.

3. A rotary screen having a plurality of screening surfaces, and inclined strips crossing the screen at alternate sides and spaced from the screening surfaces to provide tortuous passages for advancing the screen 65 contents over the screen surfaces and to the discharge end of the screen.

In testimony whereof we affix our signatures in presence of two witnesses.

JOHN M. STONE.
